(57) **CLAIM**

The ornamental design for an injection pen, as shown and described.

DESCRIPTION

FIG. 1 is a top, front, left side perspective view of an injection pen with the cap on;

FIG. 2 is a top plan view of FIG. 1;

FIG. 3 is a bottom plan view of FIG. 1;

FIG. 4 is a front elevation view of FIG. 1;

FIG. 5 is a back elevation view of FIG. 1;

FIG. 6 is a left side elevation view of FIG. 1;

FIG. 7 is a right side elevation view of FIG. 1;

FIG. 8 is a top, front, left side perspective view of the injection pen of FIG. 1 with the cap removed;

FIG. 9 is a top plan view of FIG. 8;

FIG. 10 is a bottom plan view of FIG. 8;

FIG. 11 is a front elevation view of FIG. 8;

FIG. 12 is a back elevation view of FIG. 8;

FIG. 13 is a left side elevation view of FIG. 8; and,

FIG. 14 is a right side elevation view of FIG. 8.

The evenly-spaced broken lines at the breaks in the figures illustrate portions of the injection pen that form no part of the claimed design. Any portion of the article between those breaks forms no part of the claimed design.

1 Claim, 8 Drawing Sheets
